UNITED STATES PATENT OFFICE

157,775

PLAY SHORTS OR SIMILAR ARTICLE

Bret Morrison, New York, N. Y.

Application June 15, 1949, Serial No. 3,298

Term of patent 14 years

(Cl. D3—17)

To all whom it may concern:

Be it known that I, Bret Morrison, a citizen of the United States of America, residing in New York city, county of New York, and State of New York, have invented a new, original, and ornamental Design for Play Shorts or Similar Article, of which the following is a specification, reference being had to the accompanying drawing, forming part thereof, wherein,

The back of the play shorts is identical in appearance to the front shown.

I claim:

The ornamental design for play shorts or similar article, substantially as shown and described.

BRET MORRISON.
